EUGENE A. KUEN, OF CINCINNATI, OHIO, ASSIGNOR TO THOMAS J. CORCORAN, OF CINCINNATI, OHIO.

LAMP.

1,419,062.

Specification of Letters Patent. Patented June 6, 1922.

Application filed April 7, 1919. Serial No. 288,131.

To all whom it may concern:

Be it known that I, EUGENE A. KUEN, a citizen of the United States, residing at Cincinnati, in the county of Hamilton and State of Ohio, have invented certain new and useful Improvements in Lamps, of which the following is a specification.

Lamps of the character to which this invention relates usually employ a body, a reflector, and a closure, the closure comprising a transparent or translucent sheet known as a lens, through which the rays of light are projected. Lamps of this character are usually employed as headlights, and are especially useful on motor driven vehicles.

Objects of my invention are to provide novel clamping connections between the lamp-members; to provide means whereby ready assembling may be had; and to provide simple means whereby unintentional disarrangement of the relations of the lamp-members is prevented; and the invention will be further readily understood from the following description and claims, and from the drawings, in which latter:

Fig. 1 is a front elevation of my improved device with parts of the closure, the lens, and the reflector removed, for exposure of the interior parts.

Fig. 2 is a cross-section of the same, taken on the line 2—2 of Fig. 1.

Fig. 3 is an enlarged sectional detail, taken on the line 3—3 of Fig. 2.

Fig. 4 is a cross-section detail taken on the line 4—4 of Fig. 3.

Fig. 5 is a sectional detail taken on the line 5—5 of Fig. 3.

Fig. 6 is a rear elevation detail, partly in section on the line 6—6 of Fig. 2.

Fig. 7 is a detail in perspective, showing a part of the body and a part of the closure in separated relation, and showing the axial guiding means between the same.

Fig. 8 is a cross-sectional detail, showing a modification of my improved device.

Fig. 9 is a cross-sectional detail, showing a second modification of my improved device.

Fig. 10 is a rear elevation detail of the attaching plate for the last-named modification.

Fig. 11 is a cross-sectional detail, partly in perspective, showing a third modification of my improved device.

Fig. 12 is a front elevation detail, show-

ing a fourth modification of my improved device.

Fig. 13 is a section of the same taken on the line 13—13 of Fig. 12; and,

Fig. 14 is a cross-section of the same, taken on the line 14—14 of Fig. 12.

The body is exemplified at 11. It is shown of general parabolic form, and is provided at its front end with a substantially cylindrical wall 12, at the front end of which there is an inwardly extending annular flange 13. The flange may be formed integral with the body, or, if desired, may be on a ring, as shown in Fig. 11, in which the flange is shown at 13' extending integrally inward from an annular ring 14 secured in any suitable manner, as by soldering or brazing, to the inner surface of the substantially cylindrical wall 12.

A reflector 17, shown as a parabolic reflector, is received in the body. It is provided with a laterally outwardly extending annular flange 18, which coacts with the flange 13. The flange 18 is shown as at the rear end of a rearwardly projecting annular wall 19, projecting rearwardly from the front end of the reflector, for forming an annular bulge 20, in the front end of which there is an annular groove 21 for receiving an annular cushion 22. This annular cushion may be a string of fabric or a rubber ring let into the groove.

A suitable lamp holding means, shown as an electric connector 25, is in the rear end of the reflector, being shown as in a thimble 26 fixed to the reflector, and is adjustable therein in any suitable manner, not shown because well known. Electric conductors 30 extend therefrom, and may have connection with a suitable electric connector 31, fixed in the body, for receiving an electric plug 32 having connection in any suitable manner with a source of electric power.

An electric lamp-bulb 36 is releasably secured in the electric connector 25 in usual manner, as by bayonet slot and pin connection 37.

A closure for the lamp is provided, shown as comprising a ring-member 40 and a transparent or translucent member 41, which will hereinafter be referred to as a lens. This lens is usually of glass. Clips 42 are secured to the ring-member by screws 43 and press against the lens to hold the latter in place. The ring-member conforms to the

general shape of the outer portion of the body, for instance, the forwardly extending wall 12. While the ring-member and the parts of the body and reflector coacting therewith are shown and described as annular, it is obvious that other forms thereof are included within my invention within the scope of the appended claims.

The ring-member, in the present exemplification, comprises an outer member 44 having an inwardly extending flange 45 at its front portion, which is shown annular, and a wall 46 which is arranged to coact with the wall 12, and is also shown annular. It may also comprise an inner member 47 which acts to brace the outer member and is fixedly secured thereto, as by soldering or brazing. It aids in resisting the compression exerted by the tension-members hereinafter described. The inner member comprises a wall 48 to conform to the general shape of the outer peripheral edge of the lens, and is shown annular. It positions the lens.

When the parts are assembled, the flange 18 of the reflector coacts with the flange 13 of the body, as by being received thereon, and the inner face of the lens is received against the cushion-member 22, the flange 45 projecting inwardly preferably to slightly greater extent than the cushion-member, but being proximate thereto at the outer face of the lens.

Means are provided for positioning the reflector on the body, for positioning the ring-member with relation to the body, and for clamping the parts together in associated relations.

Thus the flange 13 is provided with ears 51, these ears being preferably struck up from the body of the metal of the flange, and having a space 52 thereunder between the ears and the plane of the flange 13, in which the flange 18 of the reflector is received. The flange of the reflector is provided with recesses 53 having angular dimensions preferably at least as large as the angular dimensions of the ears, so that, when assembling the parts, the flange of the reflector may be readily received past the outwardly extending portion of the ears by axial movement of the reflector with relation to the body, and then rotated, so that the flange of the reflector is received under the ears, between the ears and the flange of the body. The ears and the walls of the recesses coat to center the reflector in the body.

The parts are clamped together by tension-members, shown as screws 56 in Figs. 1 to 11 inclusive. The screw is received through an aperture 57 in the front wall 58 of the ring-member of the door or closure, through apertures 59, 60, in the inner member 47 of the ring-member, an aperture 61 in the flange 18 on the reflector, and preferably through an aperture 62 in the flange

13 of the body. The ring-member may be of the cross-sectional form shown, or of other desirable cross-sectional form. The screw-threaded end of the screw is received in the screw threaded bore of a nut 64. The nut is fixed to the flange 13 in any suitable manner, being preferably soldered or brazed to its rear face. The head of the screw is preferably a countersunk head, that is to say, its rear face is tapered, and the wall of the hole 57 is correspondingly tapered, so that preferably the outer end-face only of the head of the screw which is preferably rounded, is in view when the parts are assembled.

The nut preferably has a tapered entrance end 65 in advance of the threaded portion of its bore, the entrance end being preferably unthreaded and spreading outwardly radially, and the apertures 60, 61, 62, larger than the diameter of the screw, so that the threaded end of the screw may be readily received therein and its threads readily connected with the threads of the nut. The threaded end of the screw is preferably split, as shown at 66, the split ends being slightly spread to press resiliently against the threaded wall of the nut to prevent unintentional unscrewing of the screw.

The nut may be secured to the flange by providing the nut 64' with an integral outwardly extending hub 68, the outer end of which is spread or riveted over the wall of the aperture 62' in the flange 13, for fixing the nut in said hole, as shown in the modification illustrated in Fig. 8. The threaded bore of the nut 64' may be preceded by a tapered entrance end 65' for the ready reception of the screw.

If desired, the nut may be formed by 105 forming a plate 70 with a rearwardly struck annular portion 71, the front end of which is tapering, as shown at 72, and the rear end of which is a threaded bore, the plate being secured to the inner face of the flange 110 13 in suitable manner, as by brazing or soldering, this modification being shown in Figs. 9 and 10.

If desired, the annular portion 71' and the tapered portion 72' of the bore may 115 have the walls thereof struck directly from the flange, as shown in the flange 13' of the modification illustrated in Fig. 11.

The reflector is provided with the opening 61, through which the screw is arranged to pass, the wall of the opening nearest the ear 51, acting as a stop to prevent rotation of the reflector in reverse direction in order to maintain its flange 18 under the ear, and to prevent unintentional removal or dropping of the reflector when removing the door or closure. A suitable number of the screws and ears may be employed, three of each being shown in alternate arrangement.

The tension-member may extend in opposite direction, for placing the head of the screw at the inside of the body, for instance in rear of the flange 13, its threaded end projecting forwardly, as shown by the threaded tension members 78, in the modification illustrated in Figs. 12, 13 and 14. When this form is employed, nuts 79 are preferably received over the forward threaded ends of the screws and the heads of the screws are preferably provided with right angular shoulders. The screws may, if desired, be fixed to the body by having their heads fixed to the flange 13, as by 15 brazing or soldering. The bores of the nuts are tapered outwardly at their rear ends, as shown at 80, to be readily received over the threaded ends of the screws. The outer ends of the threaded bores of the nuts may 20 be closed and slotted, as shown at 81, if desired, and provided with tapered shoulders 82 received against the ring-member.

When this form of tension member is employed, it is also desirable to elongate the 25 aperture 61' in the flange 18 of the reflector, so as to permit slight rotation of the reflector to place the wall of its recess 53 beyond the range of the ear 51, to permit removal of the reflector off the body. The 30 forwardly extending screws act to hold the reflector on the body and prevent accidental removal of the same.

In order to readily locate the holes in the 35 ring-member and the connecting parts in the body axially with relation to each other, the body and the ring-member are provided with coacting means to position the same rotatively with relation to each other. These means are exemplified as lugs 86 40 struck radially from the outwardly extending wall 12 of the body, the rear wall 46 of the door being provided with coacting slots 87, the walls of which coact with the lugs for relatively locating the closure and 45 body, but permitting relative movement between the closure and body parallel with the principal axis of the lamp, so as to permit clamping movement between the closure, the reflector and the body.

50 There is preferably a slight space 88 between the forward end of each of the lugs 86 and the forward end of the wall 12, so as to permit the rear edge of the closure to be received over the forward end of the 55 body, so as to center the closure on the body, the closure being then rotated on the lugs until the latter are received in the slots 87, whereby the apertures and nuts or screws respectively in the closure and body register 60 with each other, whereupon the closure is pushed axially toward the body. The movable parts of the tension-members may then be readily inserted and the same rotated for clamping the parts together. A suitable 65 number of the lugs and slots is provided,

three of each being preferred, arranged about the body. Three of the clips 42 are also preferably employed.

My improved device provides a lamp of few parts, of simple construction, readily assembled, and a lamp which is dust-proof, the cushion-member 22 between the closure and the reflector preventing dust being received between the closure and reflector, or against the inner polished reflecting face of 70 the reflector, and the flanges 13 and 18 are securely clamped together throughout their circumferences for preventing dust seeping therebetween between the wall of the reflector and the body. 80

Having thus fully described my invention, what I claim as new and desire to secure by Letters Patent, is:

1. In a lamp, the combination of a body, a reflector, and a closure, tension members 85 connecting said body reflector and closure, comprising coacting parts respectively on said body and said closure, positioning means between said reflector and said body, and positioning means between said closure 90 and said body, to axially align said coacting parts.

2. In a lamp, the combination of a body, a reflector, said reflector provided with a recess, said body provided with an ear received 95 through said recess, said ear and a wall of said recess arranged to position said reflector on said body, and said ear having a part projecting in front of said wall to axially position said reflector on said body, a closure, 100 said closure provided with a ring-member and a lens, a cushion-ring between said lens and said reflector, said body and said closure provided with coacting positioning parts in coincident projections parallel with the principal axis of said lamp for axial guidance of 105 said closure on said body when said closure and said body are assembled, and means having a manipulating part outside said lamp for clamping said body, said reflector and 110 said closure together.

3. In a lamp, the combination of a body having a substantially cylindrical wall at its forward end, a laterally inwardly extending annular flange at the forward portion of said wall, a substantially parabolic reflector the inner end of which is received in said body, said reflector having a laterally outwardly extending annular flange received in front of said flange of said body, a closure comprising a ring-member and a lens, a cushion-member between said reflector and said lens, said ring-member comprising an inwardly extending flange received in front of said lens proximate to said cushion-member 115 when said closure is assembled on said body, said ring-member provided with a rear wall coacting with said substantially cylindrical wall of said body, and screw-members connecting said ring-member with said flange of 120 125 130

said body comprising rotatable means exposed outside said lamp for clamping said body, said reflector and said closure together with said cushion-member and said lens received between said flange of said ring-member and said reflector, said annular flanges of said body and said reflector provided with coacting ears and recesses therefor having walls to limit rotative movement between 5 said reflector and said body, said flange of said reflector provided with openings, and said screw-members coacting with the walls of said openings to limit rotative movement of said walls of said recesses away from said 10 ears.

4. In a lamp, the combination of a body having a substantially cylindrical wall at its forward end, a laterally inwardly extending flange at the forward portion of said wall, a 15 substantially parabolic reflector the inner end of which is received in said body, said reflector having a laterally outwardly extending annular flange received in front of said flange of said body, a closure comprising a ring-member and a lens, a cushion-member between said reflector and said lens, said ring-member comprising an inwardly extending flange received in front of said lens proximate to said cushion-member when 20 said closure is assembled on said body, said ring-member provided with a rear wall coacting with said substantially cylindrical wall of said body, and tension-members connecting said ring-member with said flange of said body and received past said flange of 25 said reflector, said forwardly extending wall of said body provided with ribs, and said rearwardly extending wall of said ring-member of said closure provided with coacting 30 notches, and the walls of said notches and said ribs coacting to fix rotative relation between said closure and said body.

5. In a lamp, the combination of a body, a reflector and a closure, said reflector and

said body provided with coacting positioning parts for positioning said reflector in said body, and said body and closure provided with coacting guiding faces for rotative movement between said closure and body, and said body and closure provided with coacting lugs and recesses for arresting rotative movement between said closure and body and for guiding axial movement between the same. 45

6. In a lamp, the combination of a body, a reflector and a closure, said reflector received in said body, and said closure and said body at their proximate meeting edges provided with coacting guiding faces for rotative movement between said closure and said body, and said closure and said body provided with coacting lugs and recesses at points spaced from said meeting edges to arrest said rotative movement and to guide axial movement between said closure and 60 said body.

7. In a lamp, the combination of a body, a reflector and a closure, said reflector received in said body, and said closure and said body at their proximate meeting edges 70 provided with coacting guiding faces for rotative movement between said closure and said body, and said closure and said body provided with coacting lugs and recesses at points spaced from said meeting edges to 75 arrest said rotative movement and to guide axial movement between said closure and said body, and tension-members between said body and said closure to clamp said body, said reflector and said closure together. 80

In testimony whereof, I have hereunto signed my name in the presence of two subscribing witnesses.
